CLAIM

The ornamental design for laser nozzles for laser machine tools for metalworking, as shown and described.

DESCRIPTION

1. Laser nozzle for laser machine tools for metalworking
2. Laser nozzle for laser machine tools for metalworking
3. Laser nozzle for laser machine tools for metalworking
4. Laser nozzle for laser machine tools for metalworking
5. Laser nozzle for laser machine tools for metalworking
6. Laser nozzle for laser machine tools for metalworking
